(57) **CLAIM**

The ornamental design for a combined dog training device and remote control, as shown and described.

DESCRIPTION

FIG. 1 is an enlarged front elevational view of a dog training device of the combined dog training device and remote control showing our new design; the remote control is omitted for the clarity of illustration of the dog training device alone;

FIG. 2 is an enlarged rear elevational view of the dog training device shown in FIG. 1;

FIG. 3 is an enlarged left side view of the dog training device shown in FIG. 1;

FIG. 4 is an enlarged right side view of the dog training device shown in FIG. 1;

FIG. 5 is an enlarged top plan view of the dog training device shown in FIG. 1;

FIG. 6 is an enlarged bottom plan view of the dog training device shown in FIG. 1;

FIG. 7 is an enlarged front elevational view of a remote control of the combined dog training device and remote control showing our new design; the dog training device is omitted for the clarity of illustration of the remote control alone;

FIG. 8 is an enlarged rear elevational view of the remote control shown in FIG. 7;

FIG. 9 is a left side view of the remote control shown in FIG. 7;

FIG. 10 is a right side view of the remote control shown in FIG. 7;

FIG. 11 is a top plan view of the remote control shown in FIG. 7;

FIG. 12 is a bottom plan view of the remote control shown in FIG. 7;

FIG. 13 is a perspective view of the combined dog training device and remote control shown as a set;

(Continued)

FIG. 14 is a second perspective view of the combined dog training device and remote control shown as a set; and, FIG. 15 is a third perspective view of the combined dog training device and remote control shown as a set. The broken lines shown illustrate portions of the combined dog training device and remote control that form no part of the claimed design.
